(57) **CLAIM**

The ornamental design for an illuminable gaming table, as shown and described.

DESCRIPTION

FIG. 1 is a front perspective view of an illuminable gaming table showing our new design in a closed state;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a front perspective view thereof showing our new design in a partially open state;

FIG. 8 is a front perspective view thereof showing our new design in a fully open state;

FIG. 9 is a front perspective view thereof, showing our new design in a fully open state and further showing a hologram to provide example environment;

FIG. 10 is a left side perspective view thereof;

FIG. 11 is a rear perspective view thereof;

FIG. 12 is a front perspective view thereof, showing our new design in a fully open state and further showing our new design in a first illuminated state;

FIG. 13 is a front perspective view thereof, showing our new design in a second illuminated state;

FIG. 14 is a front perspective view thereof, showing our new design in a third illuminated state;

FIG. 15 is a front perspective view thereof, showing our new design in a fourth illuminated state;

FIG. 16 is a front perspective view thereof, showing our new design in a fifth illuminated state;

FIG. 17 is a front perspective view thereof, showing our new design in a sixth illuminated state;

FIG. 18 is a front perspective view thereof, showing our new design in a seventh illuminated state; and,

FIG. 19 is a front perspective view thereof, showing our new design in an eighth illuminated state.

The broken line showing of the hologram in FIGS. 9-11 and the radiating broken lines in FIGS. 12-19 are for the purpose of illustrating environmental structure that forms no part of the claimed design.

The stipple shading in FIGS. 12-19 depicts a contrast of appearance and does not depict any particular color, texture, or material.
